UNITED STATES PATENT OFFICE

1,983,946

JAR HOLDER

William Arthur Potter, Dayton, Ohio

Application March 14, 1934, Serial No. 715,550

3 Claims. (Cl. 81—3.3)

This invention relates to a jar holder, the general object of the invention being to provide means for holding a jar while the cap is being put in place or removed.

Another object of the invention is to so form the device that it can be used on different sizes and types of jars, such as small and large sizes of jars, as well as jars of cylindrical form and of square form, with means for preventing the device from breaking a jar if too much pressure is applied to the gripping means, and with means for preventing the device from slipping on a table or other support.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

25 Figure 1 is an elevation of the invention.

Figure 2 is a top plan view thereof.

Figure 3 is a section on line 3—3 of Figure 1.

In this drawing, the numeral 1 indicates a base plate which has one end bent upwardly at right angles to form the vertical support 2 and the upper end of this part 2 is bent to form the channeled part 3 which opens out at the front. Upper and lower sheets 4 of rubber or the like are fastened to the base plate 1 to prevent a jar slipping on the base of the device or the device slipping on a table top or other supporting surface. The jaw members are shown at A and each member is formed of a flat strip of spring metal turned on edge, with the rear end bent into substantially U-shape, as shown at 5, with the flat bight 6 of the U-part contacting the inner face of the bight part of the channeled member 3 and with the extremity of the short and outer limb of the U-part rolled to form an eye 7 through which a hinge pin 8 passes, this pin being adapted to pass through any one of a number of pairs of holes 9 formed in the upper and lower limbs of the channeled part 3. Thus by providing a number of these holes 9, the two jaw members may be adjusted toward or away from each other. The intermediate part of each jaw member is bent outwardly into V-shape, as shown at 10, and the inner face of this V-shaped part has a lining 11 of rubber or the like, this lining extending

over portions of the straight parts of the jaw members, as clearly shown in Figure 2. The outer portions of the two jaw members are straight and parallel so that they can be gripped by a hand of the user to move the two jaw members together in gripping relation upon a jar. An outwardly extending ear 12 is formed on one of the handle portions and a rack bar 13 has a depending ear 14 adjacent one end and these two ears are pivoted together, as shown at 15. 10 The lower edge of the bar 13 is formed with the teeth 16 for engaging the opposite handle portion, as shown more particularly in Figure 3, and the end of the bar adjacent the pivotal point is formed with a finger engaging part 17. 15

Thus it will be seen that by swinging the rack bar to inoperative position, the jaw members can be swung away from each other and a jar placed on the base of the device and then by swinging the jaw members toward each other, 20 the V-shaped parts will grip the jar and then by swinging the rack bar downwardly into engagement with the opposite handle part, the jaw members will be held in gripping relation and then the cap can be screwed onto the jar or 25 removed therefrom.

By providing each jaw member with a U-shaped part 5, if excessive pressure is applied to the handle parts of the jaw members, the jaw members will move outwardly at the U-shaped 30 portions so that breaking of a jar by excessive pressure applied to the jaw members is prevented.

It will also be seen that by the formation of the teeth 16 of the rack bar, said bar will automatically lock the two jaw members in adjusted position as the handle parts of the jaw members are moved toward each other due to the fact that the handle part which is not pivoted to the rack bar will simply slide over the teeth 40 and then will be held by a tooth from moving away from the other handle part. The flat bight parts 6 will prevent the jaw members from passing the center of the device and by making the gripping portions of the jaw members of the 45 shape shown, these jaw members will grip and hold jars of different sizes and of different shapes.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. A device of the class described comprising a base, an upright at one end of the base, a channel-shaped part at the upper end of the upright, a pair of jaw members, each having an outwardly extending U-shaped portion at one end thereof fitting in the channel, the outer limb being short and means for pivoting the extremity of the said outer limb of each U-shaped portion in the channel. 5
2. A device of the class described comprising a base, an upright at one end of the base, a channel-shaped part at the upper end of the upright, a pair of jaw members, each having an outwardly extending U-shaped portion at one end thereof fitting in the channel, the outer limb being short, means for pivoting the extremity of the said short and outer limb of each U-shaped portion in the channel with the bight of the U-shaped portion resting against the rear wall of the channel, and means for adjusting the pivotal points of the two jaw members toward and away from each other. 10
3. A device of the class described comprising a base, an upright at one end thereof, a channel-shaped member at the upper end of the upright, a pair of jaw members formed of spring material and of elongated form and each having one end bent outwardly into substantially U-shape with a straight bight for abutting the rear wall of the channel, the outer limb of each U-shaped part being short, a row of holes formed in each of the upper and lower parts of the channel adjacent the front edges thereof, the short outer limb of each U-shaped part being shaped to form an eye, a pivot pin passing through said eye and through a pair of the holes, the intermediate part of each jaw member being bent outwardly into V-shape, a resilient strip fastened to the inner face of the V-shaped part and extending over parts of the straight portions, a rack bar pivoted to the outer part of one jaw member and having its teeth adapted to engage the outer part of the other jaw member, said teeth having outer walls beveling downwardly and inwardly and having their inner walls straight. 15 20
